PRACTICE GOLF MAT

John H. Kent, Arlington, Mass.

Application December 9, 1954, Serial No. 33,460

Term of patent 14 years

(Cl. D34—5)

Fig. 1

Fig. 3

Fig. 2

Fig. 4

Fig. 5

Fig. 1 is a top plan view of a practice golf mat, showing my new design;

Fig. 2 is a side elevational view thereof;

Fig. 3 is an end elevational view thereof;

Fig. 4 is a bottom plan view thereof; and

Fig. 5 is a fragmentary cross-sectional view thereof, to an enlarged scale, taken on line 5—5 of Fig. 1.

I claim:

The ornamental design for practice golf mat, substantially as shown.
